UNITED STATES PATENT OFFICE.

WALTER R. McGINNIS, OF ST. LOUIS, MISSOURI.

REFRIGERATION-COMPRESSOR.

1,202,864.

Specification of Letters Patent. Patented Oct. 31, 1916.

Application filed September 28, 1914. Serial No. 863,799.

To all whom it may concern:

Be it known that I, WALTER R. McGINNIS, a citizen of the United States, and a resident of St. Louis, Missouri, have invented 5 certain new and useful Improvements in Refrigeration-Compressors, of which the following is a specification.

My invention relates to an improved compressor for use in refrigeration or ice-making, and has for its object to provide a compressor in the use of which stuffing boxes are dispensed with and the use of lubricants dispensed with, lessened or minimized; in the accomplishment of which object I employ 10 a piston of less diameter than its cylinder and operating in cooling fluid contained in the cylinder, and operating against a flexible or resilient suction-and-compression diaphragm.

20 In the drawings—Figure 1 is a longitudinal vertical view in section of a device embodying my invention. Fig. 2 is a top plan view of the same, a portion of the bed-plate being broken away.

25 In that embodiment of my invention which is displayed in the drawings, the bed-plate 3 is slightly concaved as indicated by the numeral 4 to serve as the head of the cylinder 5 in which the convex-faced piston 30 6 reciprocates; the diameter of the piston 6 being slightly less than that of the cylinder 5 so as to permit it to operate freely in the condensing fluid contained in the cylinder 5, which fluid is constantly fed to the cylinder 5 by the inlet-pipe 7, and conducted 35 from the cylinder 5 by the overflow-pipe 8.

Upon the bed-plate 3 the motor 9 is mounted, by which the drive wheel 10 is driven, imparting reciprocating movement to the 40 piston 6 by means of the connecting-rod 11, lever-arm 12 and piston-rod 13 as shown in Fig. 1.

I have illustrated the evaporator 14 as being mounted beneath the floor or shelf 15 upon which the bed-plate 3 is mounted. The refrigerating liquid is admitted to the evaporator 14 through the pipe 16, and its flow controlled by the valve 17. From the 45 valve 17 the pipe 18 leads to the condensing coil 19 in the cylinder 5. From the other terminus of the coil 19 the pipe 20 leads to the discharge-valve 21 in the concave cylinder-head 4.

At the end of the evaporator 14 opposite 50 to the inlet-pipe 16 the outlet pipe 22 leads to the suction-valve 23, mounted in the

cylinder-head 4. Within the cylinder 5 and above the head 4, I provide a resilient or flexible watertight diaphragm or auxiliary piston 24 which is flexed upwardly and 60 downwardly by the movement of the piston 6.

As the gas begins to form in the evaporator 14 the piston 6 is set in motion, on its upstroke drawing after it the central portion of the diaphragm 24, carrying or aspirating the gas through the suction valve 23; said gas is compressed by the return stroke of the piston 6 and diaphragm 24, and forced through the discharge valve 21 and 70 through the pipe 20 to the condensing coil 19.

By means of the described construction I have provided a compression system in which lubricant is practically dispensed with and in which no lubricant can enter 75 the condensing coil. It is well known in this art that lubricant once admitted to the condenser tends to form a thin film of such lubricant on the inner surface of the condenser coils, which acts as a non-conductor 80 of heat and reduces the efficiency of the condenser.

The condensing fluid in the cylinder 5 serves to water-jacket the diaphragm 24, preventing superheating of the gas during 85 compression and carrying off much of the heat contained in the gas. The condensing fluid assists in keeping the diaphragm 24 gas-tight, while the looseness of the piston 6 in the cylinder 5 prevents friction between 90 said piston and cylinder and the wear consequent upon such friction. Furthermore I dispense entirely with the use of stuffing-boxes, either for the piston-rod 13 or other 95 parts of my mechanism, which stuffing-boxes have required great care in construction, installation and maintenance to prevent leakage of gas, and have required ample lubrication.

Having thus described my invention, 100 what I claim as new and desire to have secured to me by the grant of Letters Patent, is—

1. In a refrigeration compressor a cylinder having a fixed head at its bottom, a flexible diaphragm mounted above said head, a piston of slightly less diameter than the cylinder and a mass of fluid contained in the cylinder above said diaphragm in combination with a condensing coil mounted within the cylinder, and an evaporator. 105
2. In a refrigeration compressor a cylin- 110

der having a concave fixed head at its bottom, a flexible diaphragm mounted above said head, a piston of slightly less diameter than the cylinder and a mass of fluid contained in the cylinder above said diaphragm in combination with a condensing coil mounted within the cylinder, and an evaporator.

3. In a refrigeration compressor a piston, 10 a condensing coil, a cylinder in which said piston and coil are mounted, and means for supplying cooling fluid to the interior of the cylinder.

4. In a refrigerator compressor, in combination, a bed-plate; a cylinder mounted vertically on said bed-plate, and having a

concave head at its bottom; a flexible diaphragm mounted in the lower end of said cylinder above said concave head; a piston of less diameter than the said cylinder; a 20 condensing coil mounted in the cylinder above said piston; and an evaporator having suitable valve connections with said cylinder at a point beneath said diaphragm.

In testimony whereof, I have signed my 25 name to this specification, in presence of two subscribing witnesses.

WALTER R. McGINNIS.
